UNITED STATES PATENT OFFICE.

JOSEPH RUBINO, OF CORONA, NEW YORK, ASSIGNOR TO NEW JERSEY PATENT COMPANY, OF WEST ORANGE, NEW JERSEY, A CORPORATION OF NEW JERSEY.

DESIGN FOR A CABINET.

45,126.

Specification for Design.

Patented Jan. 6, 1914.

Application filed October 20, 1913. Serial No. 796,344. Term of patent 14 years.

To all whom it may concern:

Be it known that I, JOSEPH RUBINO, a subject of the King of Italy, residing at Corona, in the county of Queens and State of New York, have invented a new, original, and ornamental Design for Cabinets, of which the following is a specification, reference being had to the accompanying drawing, forming a part thereof.

The figure is a perspective view of a cabinet showing my new design.

I claim:

The ornamental design for a cabinet as shown.

JOSEPH RUBINO.

Witnesses:

WILLIAM A. HARDY,
MARY J. LAIDLAW.
